UNITED STATES PATENT OFFICE.

WILLIAM R. WEBSTER, OF PHILADELPHIA, PENNSYLVANIA.

METHOD OF SPREADING THE ENDS OF RECTANGULAR METAL BARS.

SPECIFICATION forming part of Letters Patent No. 380,414, dated April 3, 1883.

Application filed August 20, 1887. Serial No. 247,415. (No model.)

To all whom it may concern:

Be it known that I, WILLIAM R. WEBSTER, of the city and county of Philadelphia, State of Pennsylvania, have invented a new and useful Improvement in the Method of Spreading the Ends of Rectangular Metal Bars to Form Eye-Bars, of which the following is a true and exact description, reference being had to the accompanying drawings, which form a part of this specification.

My invention relates to the spreading and thickening of the ends of rectangular metal bars in the process of converting them into what are known as "eye-bars" for bridges and the like.

Prior to my invention eye-bars were formed from flat rectangular bars by methods which, while differing in some details, may be grouped as follows: First, by upsetting the heated end 20 of a bar in a die of the required shape and while it was clamped between plain die-faces; second, by piling the end to be formed into an eye and then swaging the thickened end into shape; third, by upsetting the end of the bar in dies 25 in which the sides, faces, or both the sides and faces, were made to yield or move outward, so as to permit the bar to spread or spread and thicken without at any time leaving room enough for any considerable bending or buckling; fourth, by upsetting the end so as to thicken it, then upsetting the thickened end 30 in spreading dies, and then forging down the spread and thickened end to the required shape and thickness in forming dies. The necessity 35 of the two upsetting operations in the last-mentioned method arose from the difficulty found in preventing the bars from folding and buckling, the only method practiced for preventing this being to so form the dies that they 40 would engage the corners or edges of the bars, and thus support them longitudinally while being upset, a plan sufficiently effective when thickening the ends, but not practicable where any considerable spreading was required. The 45 spreading of the eye in this method was accomplished by the same means as in the first; but the preliminary thickening diminished the tendency to buckle or fold between the flat die-faces. Another method practiced was 50 by forming an enlarged end on the bar in rolling it, and spreading this end out by a hammer.

Now, I have discovered that by clamping the end of a bar heated to the temperature necessary for upsetting between die-faces, in one or both of which a longitudinal groove or depression is formed so as to lie under or over the medial line of the flat sides of the bar throughout the length of its heated end, and then upsetting the bar by pressure upon its end acting in the line of the central groove or depression, the said bar will be entirely free from any tendency to buckle or bend sidewise and will be expanded or spread evenly on both sides of its center line, the reason for this being that a longitudinal bead or projection is 60 formed all along the center of the flat side or sides of the heated bar end corresponding with and filling the longitudinal groove or grooves in the die-faces, and the end of the bar is thus, as it were, interlocked with the die-face, and 65 all tendency to bend is overcome, while the freedom of the bar to spread on each side of the center line is in nowise interfered with.

It is not at all necessary that the bar should be tightly clamped between the upper and 75 lower die-faces of the spreading die, as the first action of the upsetting-plunger will cause the soft metal of the heated end to expand into the groove of the die-face, and the continuation of the pressure only serves to increase and maintain the hold of the bead thus formed on the bar upon the grooved die-face.

I have in another application described the use of a spreading die made up of one die-face having the central longitudinal groove and another die-face having a corresponding projection, which said projection coacted with the groove in preventing buckling in the bar, and of course a plan flat-faced die might be used in connection with the grooved die. The 85 conjoint use of a grooved lower die with a similarly-grooved upper die has, however, the advantage of producing an eye which, on leaving the die, is thickest along its center line, and which, therefore, has a surplus of metal at its 90 end. As a result of this the subsequent work put upon the eye in completing it serves to consolidate and strengthen the end of the bar 95 which has to bear the strain of the pin.

Reference being now had to the drawings, 100 which illustrate dies adapted for use in my new process, Figure 1 is an end elevation of

such a die; Fig. 2, a plan view of the lower die-face. Fig. 3 is an end elevation of the die, showing the bar to be spread therein with the projecting bead formed thereon; and Fig. 4 shows in perspective a bar having along the center of each of its flat sides the longitudinal beads or projections by which it interlocks with the grooved die-faces.

A and B are the upper and lower die-faces, 10 constituting together, and with the usual cheek-pieces, plunger, &c., the spread die.

C is a flat rectangular bar of the kind for which my improved process is adapted.

1 and 2 represent the spaces into which the 15 metal of the bar is forced in the process of spreading.

b indicates the central longitudinal groove formed in the die-faces, and c indicates the bead or projection by which the flat rectangular bar is interlocked with the die-face.

From what has been already said the mode of handling the bar in carrying out my process will be readily understood. The end to be spread into an eye is first heated to the required 25 temperature and then placed in the die, so that the center of one of its flat sides will lie throughout along the longitudinal groove formed in the die-face which supports its said side. The bar is then clamped in the usual way to resist 30 a longitudinal thrust, and the upper die, which is also preferably grooved, but may be of any desired form, is placed in position upon the opposite side of the flat bar and firmly secured in place. The plunger then acts against the 35 heated end of the bar, its line of motion being parallel to the groove or grooves formed in the die-faces, and the metal of the bar is upset and forced backward into the dies. The pressure being equal in all directions, the metal will 40 flow not only into the cavities 1 and 2, but also into the grooves b, which will soon be com-

pletely filled by the metal and kept full during the whole of the upsetting action.

In cases where it is desirable that the eye 45 formed in the spreading die should have a considerable excess of metal at the center, this is easily accomplished by increasing the breadth and depth of the longitudinal grooves in the die-faces, and a very considerable thickening of the bar in the most desirable place can thus 50 be brought about.

It is of prime importance that the groove or grooves b should extend over the whole length of the heated bar end, so as to engage it from end to end and prevent the least tendency to 55 bend during upsetting, for if the free end of the bar is bent at any point it is impossible to afterward correct the distortion, and the metal in the eye will be unevenly distributed even if the distortion is not sufficient to make what 60 is known as a "buckle" or "fold."

Having now described my invention, what I claim as new, and desire to secure by Letters Patent, is—

The process of spreading the end of a rectangular metal bar, which consists in heating said end to the required temperature for upsetting, clamping it between die-faces, one or both of which are provided with a continuous central longitudinal depression or groove arranged to lie along the whole length of the heated end, and then upsetting it by pressure on its end and in the line of the central groove in the supporting die-face, all substantially as specified, and so that the heated end of the bar 75 will be distorted and engaged with the grooved die-face along its medial line and throughout its length during the upsetting.
